ABRADING WHEEL

George W. Rochwald, Kearny, N. J.

Application March 15, 1944, Serial No. 526,547

12 Claims. (Cl. 51—190)

The invention relates in particular to abrading, buffing, or polishing wheels of the type which comprises an elastic or expansible rim or annulus mounted on a supporting body in which there is means for expanding and contracting the rim to secure upon and release from the periphery of said rim respectively an endless band for abrading or other purposes.

One object of the invention is to provide an abrading wheel of this character which shall embody novel and improved means for mounting the elastic or expansible rim on the body and for expanding and contracting said rim such that the rim shall be anchored and expanded and contracted on said body uniformly throughout the circumference of the rim and the outer peripheral surface of the rim shall be substantially truly circular at all times and especially when the rim is expanded.

Another object is to provide a device of the character described the construction and combination of the parts of which shall be novel and improved so that all parts shall be capable of resisting the effects of centrifugal force and the whole device shall be simple, strong and durable.

Other objects are to provide an abrading wheel which shall embody novel and improved features of construction such that the parts can be easily and quickly assembled and disassembled; to provide such a device in which the means for expanding and contracting the expansible rim can be easily and quickly manipulated so that bands for abrading or polishing and the like can be rapidly applied to and removed from the rim, whereby interchanging of different bands on the same wheel shall be facilitated; and to obtain other advantages and results that will be brought out by the following description in conjunction with the accompanying drawings in which

Figure 1 is a front elevational view of an abrading wheel embodying my invention with portions broken away and shown in section for clearness in illustration.

Figure 2 is a transverse vertical sectional view on the line 2—2 of Figure 1.

Figure 3 is a view similar to Figure 1 showing a modification of the invention.

Figure 4 is a sectional view on the line 4—4 of Figure 3.

Figure 5 is a view similar to Figure 1 showing another modification of the invention.

Figure 6 is a side elevation of the wheel shown in Figure 5 with portions broken away and shown in section.

Figure 7 is a front elevational view of another

form of abrading wheel embodying the invention, with portions broken away and shown in section.

Figure 8 is a vertical transverse sectional view on the line 8—8 of Figure 7, and

Figure 9 is a side elevational view of the wheel.

Specifically describing the embodiment of the invention illustrated in Figures 1 and 2, the wheel includes a body which comprises a tubular hub 1 to be applied to the shaft of a motor or other suitable driving mechanism. The hub has a circumferential exterior rib or shoulder 2 intermediate its ends and two side plates 3 are fitted over the hub to form a chamber between them. A spacing sleeve 4 is interposed between each side plate and the circumferential rib 2 and a nut 5 is threaded on each end of the hub to clamp the adjacent side plate 3 firmly on the hub.

The side plates 3 are circular and are encircled at their peripheries by an expansible rim or annulus 6 which preferably constitutes a ring of rubber. A plurality of thrust members 7 are radially slidably mounted on the body of the wheel and each has one end connected to the rim 6 and its other end connected to means for expanding and contracting the rim. More particularly, each thrust member is in the form of a sheet metal plate and has one end 8 interlockingly embedded in the rubber ring 6. The other end of the thrust member has hinge knuckles or sleeves 9 which cooperate with the complementary hinge knuckles or sleeves 10 on a link 11. A hinge pintle 12 extends through the hinge sleeves 9 and 10 and has its ends slidably mounted in slots 13 in the respective side plates 3. Also, preferably each thrust member has a guide lug 14 at each of its opposite side edges slidably mounted in a slot 15 in the corresponding side plate 3.

Each link 11 has its end opposite the hinge sleeves 10 pivotally connected at 15 to an actuator 16 which is in the form of a metal disc and is journaled for rotation on the hub 1 in a plane perpendicular to the axis of the hub. Normally the ring 6 is contracted as shown in Figure 1 and the links 11 are inclined to radii of the body, but upon rotation of the actuator disc 16 in the direction of the arrow in Figure 1, the links 11 will be actuated so as to bring them into approximately radial planes of the body and the rim and thereby exert outward pressure on the thrust members 7. This in turn will expand the rim 6.

For rotating the actuator disc 16, I have shown an operating member 17 which is journaled for rotation on a stud 18 which is secured in one of

the side plates 3, and one end of the operating member extends through an opening 19 in the other side plate. The actuator disc 16 has an opening 20 through which the operating member extends and said opening has one approximately radial wall 22 with which cooperates a cam 23 carried by the operating member so that as the operating member is rotated in the direction of the arrow on Figure 1 the cam 23 will engage the surface 22 and rotate the actuator disc. The cam may have a flat surface 24 to cooperate with the straight side wall 22 of the opening 20 for holding the operating member against rotation so as to hold the actuator disc at the limit of its movement in the direction to expand the rim 6. Upon rotation of the operating member in the other direction, the resiliency of the expansible rim will force the thrust members inwardly so as to permit contraction of the rim, although, if desired, the cam 23 and the walls of the opening 20 may be so related as to cause positive actuation of the actuator disc by the cam upon rotation of the latter in both directions. It is desirable that a stop pin 25 be provided for limiting rotation of the actuator plate.

The operating member may be rotated in any suitable manner but as shown has a polygonal socket 26 to receive a pin wrench.

With this construction it will be observed that the rim can be easily and quickly contracted and expanded to permit application and removal of endless treating bands 27, such as bands having emery powder or sand on their outer surfaces. As is known in the art, such bands generally will have an internal diameter approximately equal to the external diameter of the ring 6 when the latter is contracted so that when the rim is expanded it will tightly grip the band and hold it firmly against movement on the rim 6.

It will also be observed that the structure permits the use of a large number of closely circumferentially spaced thrust members and the accurate simultaneous actuation of all thereof so that the outer peripheral surface of the rim and consequently the surface of the treating band shall be substantially truly circular at all times especially when the rim is expanded. Also, the structure will firmly resist the effects of centrifugal force, particularly to prevent expansion of the rim under the influence of centrifugal force.

Also the wheel can be easily and quickly assembled and disassembled for inspection or repair.

In the modification of the invention shown in Figures 3 and 4, the body of the wheel includes two complementary cup shaped sections 28 and 29 which are separably secured together by screws 30 with the edges of their rims 31 in abutting relation to form a chamber between the sections. One section has an integral hub 32 while the other section has an opening 33 fitted over the hub. The meeting surfaces of the rims 31 of the sections have complementary notches 34 which form radial openings in each of which is slidably mounted a thrust member 35 which has a head 36 at one end embedded in the expansible rim 37. The other end of each thrust member has pivotally connected to each of opposite sides thereof as at 38, a link 39 the other end of which is pivotally connected at 40 to a circular actuator disc 41 that is journaled for rotation on the hub 32.

The operation of this form of the invention is substantially the same as the operation of the wheel shown in Figures 1 and 2, rotation of the actuator disc 41 swinging the links 39 so as to radially slide the thrust members 35 to cause ex-

pansion and contraction of the rim 37. The actuator disc may have a hole 42 like the hole 20 with the walls of which cooperate a cam 43 like the cam 23, and the cam is rotatably mounted on a stud 44 on the body plate 28 with one end extending through an opening 45 in the other body plate 29 for the reception of a wrench or the like. In Figure 3 the rim is shown as expanded and upon rotation of the cam 43 in the direction of the arrow in Figure 3, the actuator disc will be rotated to cause the thrust members 34 to slide radially inwardly and permit contraction of the expansible rim.

Figures 5 and 6 show another modification of the invention in which the thrust members 46, links 47 and rim 56 are substantially the same as the corresponding parts of the construction shown in Figures 3 and 4. The actuator disc 48 itself has a hub 49 which is journaled for rotation on the hub 50 which is formed integrally with one section 51 on the body of the wheel. This section is cup-shaped and is closed by a plate 52 which is removably attached to the section 51 by screws 53. The hub 49 of the actuator disc projects through an opening 54 in the plate 52 and has a polygonal portion 55 by which the disc may be rotated, for example through the application of a wrench. The links 47 are connected to the actuator disc in the same manner as the links 39 are connected to the disc 41 and the expansible rim 56 is expanded and contracted as hereinbefore described by rotation of the actuator disc in opposite directions respectively. For holding the actuator disc at the limit of its movements, the disc may have a slot 57 therethrough and a pair of recesses 58 in one side of the disc leading into said slot. A pin 59 is secured to the body section 51 and extends through the slot 57, and a detent washer 59 is slidably mounted on said pin and normally influenced by springs 60 to seat in one or the other of the recesses 58. The recesses correspond to the two limits of movement of the actuator disc, and pressure of the spring on the washer and the seating of the latter in either recess 58 will releasably hold the actuator disc at one or the other of its limits of movement.

Figures 7, 8 and 9 show another form of the invention where the wheel includes a cup-shaped body section 60 which has a hub 61 and is closed by a plate 62 that is removably attached to the section 60 by screws 63. A plurality of thrust members 64 are radially slidable in the circumferential rim 65 of the body section 60, each thrust member comprising a cylindrical rod which is slidable in an opening 66 in the body and has a screw threaded end 67 which passes through a beveled pinion 68 in screw threaded relation thereto. The pinion 68 is journaled on the body as by a hub 69 which is rotatable in an opening 70 in an internal flange 71 which projects from the body section 60.

The actuator member comprises a beveled gear 72 which is journaled to rotate on the hub 61. With this construction, upon rotation of the gear 72 in opposite directions, the pinions 68 will be simultaneously rotated and through their threaded connections with the thrust members 64 will move the latter radially inwardly and outwardly respectively so as to contract or expand the expansible rim 73.

For rotating the gear I have shown it as formed with an arcuate slot 74 along one wall of which is an arcuate gear-toothed rack 75 with which meshes a pinion 76 which is carried by an operat-

ing member 77 which in turn is journaled on a stud 78 that is secured in the body section 60. The operating member has a polygonal socket 79 for the reception of a pin wrench 80 for rotating the operating member.

With this construction it will be observed that the screw threaded relation of the members to the pinions and the meshing of the latter with the gear, will positively hold the actuating gear at either limit of its movement until the operating member is actuated.

While I have shown and described several embodiments of my invention, it will be understood that this is primarily for the purpose of illustrating the principles of the invention and that many modifications and changes can be made in the details of construction within the spirit and scope of the invention.

What I claim is:

1. A wheel of the character described, comprising a body, a plurality of radially movable thrust members mounted on said body, an expandable rim to which one end of each of said thrust members is connected, and means for simultaneously actuating all of said thrust members radially in opposite directions to expand and to contract said expandable rim respectively including an actuator rotatably mounted on said body coaxially with said rim, and a link pivotally connected to each thrust member and to said actuator so that said links will be actuated longitudinally outwardly and inwardly upon rotation of said actuator in opposite directions respectively.

2. The wheel set forth in claim 1 with the addition of means for releasably holding said actuator at the limit of its movement in the direction to actuate said links outwardly.

3. The wheel set forth in claim 1 wherein said expandable rim is formed of an elastic composition, each thrust member comprises a plate extending transversely of and having one end interlockingly embedded in said rim and the other end formed with a hinge sleeve which is connected to one of said links.

4. The wheel set forth in claim 1 wherein said body has a hub, and said actuator comprises a disc journaled to rotate on said hub.

5. The wheel set forth in claim 1 wherein said body comprises separably connected complementary sections that form a chamber between them having end walls and a circumferential wall, said actuator is rotatably mounted within said chamber and said thrust members are mounted in said circumferential wall and extend therethrough.

6. The wheel set forth in claim 1 wherein said body comprises separably connected complementary sections that form a chamber between them having end walls, said actuator is rotatably mounted in said chamber and said thrust members are slidably mounted in said end walls.

7. A wheel of the character described, comprising a body, a plurality of radially movable thrust members mounted on said body, an expandable rim to which one end of each of said thrust members

is connected, and means for simultaneously actuating all of said thrust members radially in opposite directions to expand and contract said expandable rim respectively including a rotatable actuator and operative connections between said actuator and said thrust members, said actuator comprising a bevel gear rotatably mounted on said body, said thrust members including screw-threaded rods and each said operative connection comprising a bevel pinion rotatably mounted on said body in mesh with said gear and in screw threaded engagement with one of said thrust members.

5 8. A wheel of the character described comprising a body, an expandable rim, a plurality of radially movable thrust members mounted on said body and connected to said rim, and means for simultaneously actuating all of said thrust members radially in opposite directions to expand and 15 contract said expandable rim respectively including an actuator rotatably mounted on said body coaxially with said rim, and an element connecting each of said thrust members of said actuator and movable relatively to both thereof so that said 20 thrust members will be moved longitudinally inwardly and outwardly upon relative rotation of said actuator and said body in opposite directions respectively.

9. A wheel of the character described comprising a body, an expandable rim, a plurality of radially movable thrust members mounted on said body and connected to said rim, and means for simultaneously actuating all of said thrust members radially in opposite directions to expand and 25 contract said expandable rim respectively including an actuator rotatably mounted on said body coaxially with said rim, and an element connecting each of said thrust members of said actuator and movable relatively to both thereof so that said thrust members will be moved longitudinally inwardly and outwardly upon relative rotation of said actuator and said body in opposite directions respectively.

30 10. The wheel set forth in claim 8 with the addition of means for rotating said actuator including an operating member rotatably journaled on said body and an operative connection between said operating member and said actuator such 35 that the latter is rotated upon rotation of said member and to said actuator respectively, said links being normally inclined to radii of said rim with the latter contracted and being actuated into approximately radial planes of said rim to expand said rim upon relative rotation of said actuator and said body.

40 11. The wheel set forth in claim 8 with the addition of means for rotating said actuator including an operating cam rotatably mounted on said body, and wherein said actuator has a surface engaged by said cam such that the actuator is rotated upon rotation of said operating member.

45 12. The wheel set forth in claim 8 wherein said actuator has a transverse opening therethrough, and with the addition of an operating member 60 rotatably mounted on said body and extending through said opening to operatively engage the walls thereof so that upon rotation of said operating member said actuator will be rotated.

65

GEORGE W. ROCHWALD.
